US0D1028328S

(12) **United States Design Patent** (10) Patent No.: **US D1,028,328 S**
(45) Date of Patent: ** May 21, 2024

(54) **PROJECTOR LAMP**

(71) Applicant: **Zhongshan Lingli Technology Co., LTD**, Zhongshan (CN)

(72) Inventor: **Shengjia Zhang**, Yunfu (CN)

(73) Assignee: **Zhongshan Lingli Technology Co., LTD**, Zhongshan (CN)

(**) Term: **15 Years**

(21) Appl. No.: **29/922,582**

(22) Filed: **Dec. 22, 2023**

(51) LOC (14) Cl. **26-05**

(52) U.S. Cl.

USPC **D26/99**
